ATTORNEY

UNITED STATES PATENT OFFICE

FELIX R. CHAUDET, OF ST. LOUIS, MISSOURI

COMBUSTION ENGINE

Application filed September 22, 1927. Serial No. 221,383.

My invention relates to internal combustion engines, and more particularly to an internal combustion engine in which steam is injected into the cylinder during the working stroke, and the water vapor of the exhaust gases is condensed and again utilized for generating steam and for cooling purposes.

The object of my invention is to recover a portion of the waste heat of the exhaust 10 gases and utilize it for generating steam.

Another object of my invention is to provide means for condensing the water vapor of the exhaust gases and return it to the water-jacket of the engine for the dual purpose of 15 cooling the engine and of generating steam.

Other objects and advantages of my invention will be disclosed in the description, claims and drawings.

In the drawings:

20 Fig. 1 is a side elevation of an engine and condenser, showing my improvement.

Fig. 2 is a vertical cross-section of a cylinder showing my method of generating steam by passing the exhaust pipe through the 25 water-jacket.

Fig. 3 is an end elevation of my condenser, partly broken away.

It is well known that the average thermal efficiency of combustion engines operating 30 upon the Otto cycle is about 20%, the other 80% of the heat of combustion being dissipated by means of convecting currents of air, by radiation and exhaust losses, some authorities declaring the losses to the exhaust to be 35 equal to one-half of the heat generated by combustion. It is the purpose of my invention to conserve as far as possible the waste heat of the exhaust gases.

40 It is well understood that in the combustion of hydrocarbon fuel, the hydrogen content of the fuel unites with the oxygen of the air in the exact proportion necessary to produce water vapor, so that for every gallon of gasoline burned, about five quarts of water are discharged from the exhaust pipe. It is my purpose to condense the water vapor of the exhaust and make it available for use in the radiator and water-jacket to cool the engine, 45 so that it will be possible for a motor to

cross the Sahara Desert without carrying additional water supply.

Another purpose of condensing the water vapor of the exhaust is to convert it into steam to be injected into the working cylinder 55 during the working stroke, thereby to increase the efficiency of the motor.

It is, of course, understood that the steam so injected will be superheated to a point where the steam pressure will be greater than 60 the pressure of combustion at the instant the steam is injected into the cylinder.

To accomplish the above-outlined results, the normal water-jacket 1 has been sufficiently enlarged to constitute a steam boiler, while 65 the exhaust pipe 2 is wound around the cylinder 3, but spaced apart therefrom a sufficient distance to permit of water circulating between the cylinder wall and the exhaust pipe.

After the exhaust pipe has been coiled around 70 the cylinder, it passes through the water-jacket 1 into the condenser 5, where it is again turned into a plurality of coils 6 to permit of the largest possible cooling surface. The exhaust is then discharged into a 75 reservoir 7, as indicated at 8, the exhaust gases being discharged from the chamber 7 through a pipe 9, the condensed water being led back by the pipe 10, to a suitable pump 11, which pumps it back into the water-jacket as 80 indicated at 12.

In operation only the lower portion of the water-jacket is filled with water, the water line being intermediate of the ends of the working cylinder. One or more coils of the 85 exhaust pipe are thereby submerged in water which causes the water to boil and generate a vapor, which in turn contacts with the upper coils of the exhaust manifold, which are, necessarily, at a much higher temperature 90 thereby superheating the steam and raising a pressure greater than the pressure normally obtaining during the working stroke of the motor, hence the upper portion of the water-jacket, indicated as 13, becomes a steam dome 95 wherein the steam is superheated.

A valve mechanism, consisting of a plunger 14, operated by cams 15, is so designed that at every working stroke, the steam duct 16 registers with the port 17, permitting the passage 100

of steam through the port 17, through the duct 16, and the port 18 into the working cylinder during the working stroke thereof.

My engine is equipped with a proper lubricating system, intake manifold, and all other necessary and component parts of a combustion engine, these portions being neither shown or claimed as new.

The operation of the motor having been clearly disclosed in the specification, what I claim as new and useful and desire to protect by Letters Patent is:—

1. A combustion engine having a water-jacketed cylinder having a piston reciprocable therein, means for condensing water from the gases exhausted from said engine, means for discharging a portion of said condensed water into the water-jacket of said cylinder, means for generating steam within said water-jacket, means for superheating the steam within said water-jacket, means for injecting said superheated steam into the cylinder of said engine during the working stroke of the piston.
2. A combustion engine of the class described, having a water-jacketed cylinder and a piston reciprocable therein, means for transmitting heat from the exhaust gases of said engine to water within the water-jacket of said engine, means for maintaining water in said water-jacket at a substantially pre-determined water level whereby the upper portion of the water-jacket will function as a steam dome, means for transmitting heat from the exhaust gases of said engine to the said upper portion of said water-jacket whereby the water vapor rising from the water in said water-jacket will be converted into superheated steam, means for conducting and discharging said superheated steam into the cylinder of said engine during the working stroke of the piston thereby to increase the pressure against the piston to impel it upon its working stroke.
3. In witness whereof I have hereunto affixed my signature this 13th day of September, 1927.

FELIX R. CHAUDET.
